AERATION NOZZLE FOR A HYDROTHERAPY
UNITClifford E. Grube, Niles, Ill., assignor to
Associated Mills, Incorporated

Filed July 26, 1973, Ser. No. 382,707

Term of patent 14 years

Int. Cl. D23—01

U.S. Cl. D23—34

FIG. 1.

FIG. 2.

FIG. 3

FIG. 4.

FIG. 1 is a side elevation of an aeration nozzle for a hydrotherapy unit showing my new design;

FIG. 2 is a top plan view thereof;

FIG. 3 is an end elevation as seen from the left of FIG. 1; and

FIG. 4 is an end elevation as seen from the right of FIG. 1.

I claim:

The ornamental design for an aeration nozzle for a hydrotherapy unit, as shown.
